TACK HANDLING AND DRIVING MECHANISMS

William Arthur Barton, Kenneth Blanchard Pulford, and Arthur Alan Rivington, Leicester, England, assignors to United Shoe Machinery Corporation, Flemington, N. J., a corporation of New Jersey

Application February 2, 1952, Serial No. 269,654

Claims priority, application Great Britain
February 22, 1951

12 Claims. (Cl. 12—10.7)

This invention relates to tack driving mechanisms wherein the tacks are separately received from a tack feeding source into a tack driving throat, and in particular it relates to a novel and improved mechanism for presenting the tack to a work piece and for driving the tack "home" into the work piece while preventing a very small tack head from being punched through the work piece by the driver.

Although the hereinafter illustrated embodiment of the invention is shown, by way of example, as applicable to a machine for conforming shoe uppers to the shapes of lasts within the uppers, it will be understood, of course, that the present invention is of broader utility and, therefore, not limited either to use in a shoe lasting machine or to a device of the exact mechanical construction shown. The illustrated embodiment relates to a step-by-step lasting machine, such, for instance, as the general type disclosed in United States Letters Patent No. 584,744, granted June 15, 1897, on an application filed in the name of S. W. Ladd et al.; such machines being commonly known in the shoe manufacturing trade as "hand method lasting machines."

In the lasting of shoe uppers by machines of the above-mentioned type, and particularly in securing the marginal portion of an upper in lasted relation to a shoe bottom member (e. g. an insole) by means of tacks, it is sometimes desired to use relatively light and short tacks, especially when the upper and insole materials are of a relatively light character. For this purpose it is not uncommon to employ tacks some three-sixteenths of an inch or less in length. The advantages obtained from the use of these very small or "micro" tacks are the minimizing of the extent to which the points of the tacks must be clinched over on the interior of a shoe, and the minimizing of the weight of metallic-fastening material in the finished shoe. Tack-separating and feeding mechanisms suitable for handling small tacks of this kind are illustrated and described in United States Letters Patent No. 2,491,614, granted December 20, 1949, on an application filed in the name of F. B. Keall; one of said mechanisms being therein described as adapted for operation in conjunction with hand method lasting machines of the type disclosed in the previously-mentioned patent to Ladd et al. As is well known in the art of shoemaking, a lasting machine of this kind has a gripper for pulling an upper over a last successively in different locations as the last with an upper and an insole assembled thereon is presented in different positions by the operator, a wiper movable inwardly over the bottom of the last to wipe the marginal portion of the upper inwardly over the outer face of the insole, and a driver for driving a tack through an opening in the wiper to fasten the tensioned marginal portion of the upper in lasted position to the insole.

It has been found that when using a machine of the kind above referred to, fitted with tack-inserting means adapted to insert small tacks having greatly reduced tack head areas, there is a tendency, on occasions, for the

driver of the tack-inserting means to punch a small tack head through the upper material in the act of driving a tack thereinto. This is particularly noticeable when lasting around the toe portions of shoes or along the waist portions of high-heeled shoes. When operating around the toe portion of a shoe, the operator must cause the machine to effect a pleating action on the upper, and, as these pleats are formed, the general level of the shoe bottom is lowered somewhat with respect to the wiper. Hence, in order to insure that the tacks are driven fully "home," the operator usually sets the driver mechanism so that the driving face of the driver protrudes, at the end of its tack-driving stroke, some little distance (usually of the order of one-eighth inch) below the bottom face of the wiper with the result that if a tack is driven at one of the higher levels defined by one of the pleats the head of the tack is driven through one or more layers of the upper material. Similarly, when operating along the waist portions of a shoe mounted upon a last designed to accommodate a comparatively high heel, the sharply curved portion (considered height-wise of the shoe) of the last bottom, rearwardly of the ball line may not in some locations be held flush with the under face of the wiper, thus leaving a space between that face and the upper. In the latter instance it has also been found by the operator that in order to assure that the tack is well-driven "home" to form a tight clinch, the driver face should protrude a substantial amount beneath the bottom face of the wiper. However, in other locations where the portion of the upper being operated upon may be held flush up against the wiper bottom, the same degree of protuberance of the driver will cause the tack to be overdriven into the work so that the small tack head frequently punctures the upper material.

While the above-described difficulty occurs most prevalently in connection with the driving of very small tack heads, the utility of this invention is in no way limited to the use of "micro" tacks, because it has been observed that, under certain conditions, tacks having relatively large heads may be overdriven, thus causing the upper material to be punctured by the head of the tack. The latter instance has been particularly observed, in connection with larger tack heads, when the upper material is of poor grade or thin leather which is backed with an overplump fabric material as a lining.

It is one of the various objects of this invention to provide improved fastening inserting means, particularly suitable for use in a machine of the kind above referred to, by the employment of which such tendency for the driver to punch through the upper material is minimized.

Another object of this invention is to provide a novel tack driving mechanism which permits the driver uniformly to drive "home" each tack head by employing a driving stroke of sufficient extent forcefully to reach, in each instance, the work surface even though the proximity of said surface may vary somewhat for the reasons as above stated.

The illustrative machine hereinafter described is provided with tack inserting means which include a tack receptacle in the form of a nozzle movable with the wiper and arranged, first, to receive a tack just prior to the wiping operation and while in a tack receiving position, and then to move over the work during the wiping operation into a position beneath and in alignment with the tack driver so that the driver may be operated through a tack passage or throat in said nozzle; the tack being controlled during the driving thereof by means of tack controlling fingers associated with the nozzle in a well-known manner.

With the above-mentioned objects in view, and in accordance with another feature of the invention, this nozzle of the herein illustrative machine, in addition to being

movable with the wiper from tack receiving position into tack driving position, is also arranged as to be movable, in the direction of movement of the driver, relatively to a carrier for the nozzle and wiper. This latter movement of the tack nozzle, toward the work piece, preferably commences toward the end of the operative stroke of the driver, at a time when the head of the fastening, being driven, has reached close proximity with the upper surface of the work piece, and this movement of the nozzle continues concomitantly with the driver throughout the remainder of the driving stroke, so that, in completing its tack inserting stroke, the driver is only allowed to protrude beyond the end of the nozzle a controllable amount, for example, one-thirty-seconds of an inch. The throat end of the nozzle, through which the driver protrudes but slightly, is provided with a work-engaging surface closely encircling the driver and disposed as to be substantially parallel with the work in the vicinity of the head of the tack; so that, when the work-engaging surface is pressed downward upon the work, the upper material is prevented from rising unduly around the driver as the tack is driven "home." By thus keeping the upper material compacted or crowded down to approximately the level of the head of the fastening, the risk of having the driver or the head of the tack punched through the material is greatly minimized. Upon completion of the driving stroke, the driver is retracted and the nozzle of the tack inserting means is returned upward relative to its carrier by spring means. In the illustrated embodiment of this invention, the downward movement of the nozzle into work-engaging position is effected as a result of engagement with a member attached to the movable driver bar.

The above and other objects and features of this invention will appear from the following detailed description of the preferred embodiment thereof, illustrated in the accompanying drawings, and will be pointed out in the claims. It is, however, to be clearly understood that the utility of the invention about to be described is in no way limited to a machine of the type illustrated.

In the accompanying drawings:

Fig. 1 is a right-hand side elevation, on an enlarged scale, of fastening inserting means and a wiper associated therewith illustrative of this invention;

Fig. 2 is a fragmentary plan view of parts seen in Fig. 1;

Fig. 3 is an inverted plan view of parts seen in Fig. 1, the wiper being removed;

Fig. 4 is a section on the line IV—IV in Fig. 1, but showing a driver approaching the completion of its driving stroke;

Fig. 5 is a section, similar to Fig. 4, except that the driver has advanced to the completion of its driving stroke; and

Fig. 6 is a skeleton view, in perspective, showing one manner in which the fastening inserting features of this invention may be applied to a "hand method" type of lasting machine.

Referring to these drawings, and particularly to Fig. 1, the improved tack inserting mechanism of this invention is, therein shown as applicable to the above-designated "hand method" type of lasting machine. Due to the well-known characteristics and operating features of this illustrative type of machine, only so much of the machine will be described herein as is necessary to the understanding of the illustrated embodiment of the present invention. The improved tack inserting mechanism includes a novel tack receptacle in the form of a nozzle, generally indicated as 1, yieldably supported within a socket or guideway 3, extending vertically through the forward endmost portion of a carrier block 5. In addition to supporting the tack receptacle 1, this carrier 5 also serves as a support for a wiper 7 by means of which marginal portions of the upper are wiped inwardly over the bottom face of the insole, as they are released by the

gripper in preparation for the tack driving operation. As is well understood by those familiar with the hand method type of lasting machine, the carrier block is reciprocated by power means in timed relation to the tack separating and tack driving instrumentalities, so that, when the carrier 5 is moved rearwardly in the machine, a tack receiving passage 9, extending vertically through the center of the tack receptacle is in position to receive a tack which has just been separated from the tack supplying source; and when the carrier block 5 is moved forwardly the receptacle is thereby moved from tack receiving to tack driving position. An example of means whereby a tack driver and a tack receptacle may be cooperatively actuated, as above described, by the power drive shaft of a "hand method" type of lasting machine is illustrated by Fig. 6. It is to be noted that the arrangement of the operating parts therein illustrated corresponds directly to the arrangement shown in Fig. 28 of the previously-mentioned patent to Ladd et al, with the exceptions that the tack receptacle 20 of said patent has been replaced by the novel tack receptacle shown in Fig. 1 of the present application, and also a novel abutment member 43, to be described hereinafter, has been attached adjacent the lower end of the driver operating mechanism so as to be engageable with the tack receptacle upon the descent of the driver. In order to facilitate a comparison of Fig. 6 with said Fig. 28 of the patent, the various parts shown in both of these figures bear the same corresponding designating characters except that the above-mentioned novel parts, which constitute the subject of this invention, are identified by numerals corresponding to the designations used in Fig. 1 of the present application:

Referring to Fig. 6, the carrier block 5, with its tack receptacle, is rigidly affixed beneath a forward extremity of a slide carriage comprised of a horizontal arm 84 and a vertical arm 85, the arm 84 being slidably supported upon the machine frame to permit forward and rearward movement of the carriage. A pivotal lever 87, connected at one end to the arm 84, is engaged at its other end by a cam 88 which is rotated on the main power shaft of the machine. Thus, during each revolution of the cam 88, the carriage is reciprocated to move the tack carrier block between its tack-receiving and tack-driving positions. A tack driver and a tack-receptacle-engaging abutment member 43 are both adjustably secured to the lower extremity of a tack driver bar 90. The driver bar is mounted for vertical operation along a slide groove formed in the forward face of the vertical arm 85, and the bar is lifted, against the force of a rod-type torsion spring 93, by a cam 91 engaged with the underface of an offset horizontally extending shoulder (not shown) on the bar 90. The cam 91 is driven by the power shaft through a splined coupling so as to permit axial sliding movement of the cam on the shaft, which movement is necessary to accommodate the forward and rearward movements of the carriage. The work face of this cam 91 is provided with an abrupt drop-off so that with each revolution of the cam the elevated driver bar will be suddenly released by the cam to the downwardly-directed driving force of the spring 93.

The tack receptacle 1 has a concentrically shaped body portion comprising a cylindrical mid-portion 11, a head portion 13 having an enlarged diameter and a frusto-conical lower portion 15, all formed integrally with each other. As may be seen, the tack receiving passage 9 is provided with a beveled portion forming an enlarged opening at the top of the head portion 13 to facilitate the reception of a tack and the insertion of a driver 17 which traverses the passage 9 to drive the tack into the work. The receptacle 1 is inlets at diametrically opposite sides from top to bottom to provide slots 19, 19' within which are housed a pair of tack controlling fingers 21, 21' pivotally supported by pins 23, 23 carried by the main body 75 of the tack receptacle. These tack fingers are pivotally

urged toward each other by springs 25, 25 having their forward ends resiliently located within notches 27, 27 formed in the fingers, while the rearward ends of the springs are clamped to the carrier block 5 by means of a bolt 29 and nut 31. In addition to pressing the tack fingers into closed position, the springs 25 also serve to urge the entire tack receptacle or nozzle assembly upwardly to a raised position in its guideway in the carrier, the upward force of the springs being transmitted to the body of the receptacle through the fingers 21 and their pivot pins 23. This upward movement of the receptacle is limited by the engagement of an upper face 33 thereon with a cover plate 35 secured to the top of the carrier block 5, Fig. 4. The plate 35 has an opening therethrough concentric with the tack passage 9 of the receptacle to receive an upwardly extending portion 37 of the receptacle body. The lower extent of the tack passage 9 is defined by an annular work-engaging member 39 having a bore only slightly larger than the diameter of the driver 17. This member 39 is brazed, or otherwise suitably secured, to the bottom face of the conical portion 15 of the tack receptacle body.

Secured to the driver bar, by which the driver 17 is reciprocated, is a leg 41 having a cylindrical abutment foot 43 which, when depressed by the driver mechanism, is adapted to engage the elevated portion 37 of the tack receptacle thus bearing downward upon the body of the receptacle to overcome the upward force of the springs 25. As viewed in Fig. 4, the driver 17 has passed through the passage 9, through the tack fingers and is protruding a slight extent beyond the lower levels of the work-engaging member 39 and wiper 7. At this phase of the driving stroke the abutment foot 43 engages portion 37 of the receptacle body so that continued downward movement of the driver and abutment foot carries the entire tack receptacle or nozzle assembly downward a like amount thus maintaining the relative position of the driver face with respect to the work-engaging member 39 up to the completion of the driving stroke, as illustrated in Fig. 5. It is to be noted that the wiper 7, in the vicinity of the tack nozzle, is relieved to provide sufficient clearance for the nozzle assembly at the completion of the tack driving operation.

It is to be understood that the downward extent of the driver stroke is adjustable, as is customary, by locking the driver at different elevations with respect to its driver bar. In like manner the degree to which the tack nozzle participates in the downward movement of the driver may be regulated by adjusting the horizontal position of the abutment foot 43 with respect to the driver bar or driver 17; thus, by setting the leg 41 higher with respect to the position of the driver bar, the extent to which the member 39 protrudes beneath the wiper may be decreased. Such a setting might be desirable when only operating upon work presenting a perfectly flat or even surface to be tacked. Where, however, due to irregularities in the surface contour of the work, the heads of tacks, after having been properly driven "home," may be disposed at various levels, it is desirable to set the abutment foot 43 lower so that during the actual driving operation the nozzle member 39, in each instance, will be sufficiently depressed to bear downward upon the work surface in the vicinity of the tack head, thus consolidating the material and minimizing any risk of its bulging up around the driver as the tack is driven "home." The fact that the driver is adjusted so as only to protrude a slight distance beyond the lower surface of the nozzle also tends to insure that the driver does not punch through the material even though the driving face of the driver may extend a substantial distance below the lower face of the wiper.

Having described the invention, what is claimed as new and desired to be secured by United States Letters Patent is:

1. In a fastening inserting machine provided with a reciprocating tack driver mechanism and a tack receptacle carrier block movable between a tack driving position in axial alignment with the driver and a tack receiving position laterally removed from the axis of the driver, a tack receptacle yieldably supported within an opening extending heightwise through said carrier block so as normally to maintain the lower nozzle portion of the receptacle in a retracted position within the block, and means responsive to the operation of the driver mechanism for movably engaging the receptacle to force it downward during the final phase of the driving operation.

5 2. A fastening inserting machine as recited in claim 1, wherein the tack receptacle is provided with tack controlling fingers each of which is pivotally mounted on the body portion of the receptacle and movable within a recess in the receptacle, and resilient means each secured to the carrier block and movably connected to one of said fingers, said resilient means, fingers and pivotal mountings on the receptacle body portion being so constructed and arranged with respect to each other that the fingers are urged laterally toward each other for controlling the tack and at the same time urged heightwise yieldably to support the receptacle within the carrier block.

15 3. In a fastening inserting machine provided with a reciprocating tack driver mechanism and a tack receptacle carrier block movable between a tack driving position in axial alignment with the driver and a tack receiving position laterally removed from the tack driving position, a tack receptacle yieldably supported within an opening extending heightwise through said carrier block so as normally to maintain the lower nozzle portion of the receptacle in a retracted position within the block, and means responsive to the operation of the driver mechanism for movably engaging the receptacle when the driver protrudes a predetermined distance beyond the nozzle to force it downward during the final phase of the driving operation, whereby the tack engaging face of the driver may only extend a controlled amount beneath the level of the nozzle portion regardless of the magnitude of the driving stroke.

25 4. In a fastening inserting machine, provided with a reciprocating tack driver, the combination of a tack receptacle having a nozzle surface engageable with the work, carrier means operable in timed relation to the driver for moving said receptacle in directions extending transverse to the axis of the driver between tack receiving and tack driving positions, yieldable supporting means normally biasing the receptacle heightwise so as to position the nozzle surface a distance above the work, and movable means responsive to the descent of the driver and arranged to engage the receptacle when the tack-engaging face of the driver protrudes a predetermined distance beneath the nozzle surface, whereby, during the remainder of the descending stroke of the driver, the receptacle is moved concomitantly therewith to press its nozzle surface downward upon the work in the vicinity surrounding the face of the driver.

30 5. In a fastening inserting machine, providing with a reciprocating tack driver, the combination of a tack receptacle having a nozzle surface engageable with the work, and yieldable tack controlling fingers above said surface for presenting a tack in proper axial alignment to the driver, carrier means operable in timed relation to the driver for moving said receptacle in directions extending transverse to the axis of the driver between tack receiving and tack driving positions, tack receptacle supporting means normally biasing the receptacle heightwise so as to position the nozzle surface a distance above the work, and abutment means responsive to the descent of the driver and arranged to engage the receptacle when the tack-engaging face of the driver protrudes a predetermined distance beneath the nozzle surface, whereby, during the remainder of the descending stroke of the driver, the receptacle is moved concomitantly therewith

to press its nozzle surface downward upon the work in the vicinity surrounding the face of the driver.

6. In a fastening inserting machine, provided with a reciprocating tack driver, the combination of a tack receptacle having a nozzle surface engageable with the work, carrier means operable in timed relation to the driver for moving said receptacle in directions extending transverse to the axis of the driver between tack receiving and tack driving positions, yieldable supporting means urging said receptacle heightwise so as normally to maintain the nozzle surface above the work in spaced-apart relation thereto, and movable means responsive to the descent of the driver and arranged to engage the receptacle when the tack-engaging face of the driver protrudes a predetermined distance beneath the nozzle surface, whereby, during the remainder of the descending stroke of the driver, the receptacle is moved concomitantly therewith to press its nozzle surface downward upon the work in the vicinity surrounding the face of the driver.

7. In a fastening inserting machine, provided with a reciprocating tack driver, the combination of a tack receptacle having a nozzle surface engageable with the work, and yieldable tack-controlling fingers above said surface for presenting a tack in proper axial alignment to the driver; carrier means operable in timed relation to the driver for moving said receptacle in directions extending transverse to the axis of the driver between tack receiving and tack driving positions, resilient means urging said receptacle heightwise so as normally to maintain the nozzle surface above the work in spaced-apart relation thereto, and abutment means responsive to the descent of the driver and arranged to engage the receptacle when the tack-engaging face of the driver protrudes a predetermined distance beneath the nozzle surface, whereby, during the remainder of the descending stroke of the driver, the receptacle is moved concomitantly therewith to press its nozzle surface downward upon the work in the vicinity surrounding the face of the driver.

8. In a step-by-step lasting machine, provided with a reciprocating tack driver and a wiper surface on the lower face of a carrier block reciprocally operated in timed relation to the operation of the driver, the combination of a tack receptacle supported within said block and carried thereby in directions extending forwardly and rearwardly of the machine between tack receiving and tack driving positions, a work-engaging member defining the lower end of said receptacle; means urging said receptacle and work-engaging member heightwise normally to maintain the member at a level above the wiper surface, and means movably engageable with said receptacle during the driving operation to displace said receptacle downward through an opening in the wiper to thereby force the work-engaging member against the work in the vicinity of the driver.

9. In a step-by-step lasting machine, provided with a reciprocating tack driver and a wiper surface on the lower face of a carrier block reciprocally operated in timed relation to the operation of the driver, the combination of

a tack receptacle supported within said block above the wiper surface and carried thereby in directions extending forwardly and rearwardly of the machine between tack receiving and tack driving positions, a work-engaging member defining the lower end of said receptacle; resilient means carried by said block for urging said receptacle and work-engaging member heightwise normally to maintain the member at a level above the wiper surface, and abutment means engageable with said receptacle during the driving operation to positively displace said receptacle downward through an opening in the wiper to thereby compact the work-engaging member against the work in the vicinity of the driver.

10. In a step-by-step lasting and tack driving machine provided with tack driving mechanism, a wiper carrier block, a tack receptacle accommodated in a socket extending heightwise in said block above the wiping surface, said receptacle having a passage therethrough for the reception of a tack and tack driver, a work-engaging member surrounding the nozzle end of said passage, yieldable means urging said receptacle heightwise normally to maintain said member at a level above the wiping surface, and abutment means movable downward, during the fastening-inserting stroke of the driver, into engagement with said receptacle, to displace said receptacle downward through an opening in the wiper to thereby force the work-engaging member against the work in the vicinity of the driver.

11. In a fastening inserting machine, the combination with a reciprocating tack driver, of a tack receptacle alternately movable in directions transverse to the path of the driver between tack receiving and tack inserting positions and in directions along the path of the driver, said receptacle having a lower nozzle surface of decreased width engageable with the work to provide a high pressure impact thereupon, means for yieldably supporting the receptacle in spaced-apart relation to the work during said transverse movement, and means engageable with the receptacle during the descent of the driver to cause said nozzle surface to be driven into contact with the work.

12. In a fastening inserting machine, the combination with a reciprocating tack driver, of a tack receptacle alternately movable in directions transverse to the path of the driver between tack receiving and tack inserting positions and in directions along the path of the driver, means for yieldably supporting the receptacle in spaced-apart relation to the work during said transverse movement, and means engageable with the receptacle during the descent of the driver to cause the nozzle end of the receptacle to be driven into contact with the work in the vicinity of the driver.
